UNITED STATES PATENT OFFICE.

GEORGE HEITLER, OF NEW YORK, N. Y.

ANTISLIPPING DEVICE.

1,319,074.

Specification of Letters Patent. Patented Oct. 21, 1919.

Application filed February 1, 1919. Serial No. 274,466.

To all whom it may concern:

Be it known that I, GEORGE HEITLER, a citizen of the United States, residing at New York, in the county of New York and State of New York, have invented new and useful Improvements in Antislipping Devices, of which the following is a specification.

This invention relates to a safety attachment, designed for use in connection with 10 boots, shoes or other foot-gear, to prevent slipping or sliding and the injuries which frequently result therefrom.

The principal objects of the invention are: (1) to provide antislipping devices for 15 boots, shoes and the like, designed to give the user a firm hold or footing when walking on wet, icy, or otherwise slippery streets, when ascending or descending inclined places, or when climbing precipitous regions; 20 (2) to provide devices of this character which may be readily attached to and as readily removed from, the boots or shoes by the user himself; and (3) to provide devices of this character which are simple in 25 construction, comparatively inexpensive to manufacture, and efficient in service.

With the foregoing objects and others in view, the invention resides in the details of construction hereinafter described, defined 30 in the claims, and illustrated in the accompanying drawings, forming a material part of this specification, and in which:—

Figure 1 is a view in side elevation of a shoe, showing my anti-slipping devices applied thereto.

Fig. 2 is a plan view of the underneath side of the shoe, showing the devices applied.

Fig. 3 is a sectional view, taken in the direction of line 3—3 of Fig 2.

Fig. 4 is a fragmental view, taken in the direction of line 4—4 of Fig. 2.

Fig. 5 is a sectional view, taken in the direction of line 5—5 of Fig. 2.

Fig. 6 is a fragmental top plan view, the same illustrating in particular how the hook-shaped parts or ends are engaged over the sole of the shoe.

In the accompanying drawings, the number 50 7 is employed to denote a shoe, made with the usual sole element 8 and with the usual heel element 9, to which, respectively,

I may attach the anti-slipping devices as 10 and 11.

Each device is formed from a single bar 55 or length of metal, preferably of steel of a relatively resilient character, although it may be made of other suitable materials. Each bar or length, between its extremities, is bent upon itself in the same plane, first 60 forwardly and then rearwardly, providing curved obliquely-projecting forward portions 12 and curved obliquely-projecting rear portions 13. The intermediate portion or region, thus sinuously bent, is provided, on its 65 underneath side with a concave channel 14 so as to produce the confronting edges 15.

As best seen in Figs. 3 and 6, the extremities of the device 10 are bent first upwardly as at 16 and then inwardly as at 17, forming 70 hook-like parts which engage over the edges 18 of the shoe sole, whereby this device is secured in place in an obvious manner.

From Figs. 4 and 5, it will be seen that 75 the extremities of the device 11 are bent upwardly to provide lugs as 19, which are corrugated as at 20 on their inner faces so as to firmly grip the heel 9.

Being made of resilient material and with 80 the curved portions 12 and 13, the devices 10 and 11 can be stretched longitudinally for a degree sufficient to permit of the ready application and removal. By reason of their intermediate sinuous regions, which are provided on their undersides with the confronting gripping edges 15, these devices give the wearer a firm hold or footing, when walking on slippery streets or pavements, and when crossing inclined or precipitous regions. 85

From the foregoing taken in connection with the accompanying drawings, it will be readily understood that either of the anti-slipping devices may be used effectively without the other; and it will also be understood that changes and alterations in the precise details of the invention, as herein set forth and illustrated, may be made, to which changes and alterations the inventor is entitled, provided the same are effected 95 100 within the scope of what is claimed.

Having thus described my invention, what I claim is:—

1. An anti-slipping device for boots, shoes

and the like, consisting of a single length of resilient material provided with a sinuously bent intermediate region, concaved in cross-section to produce gripping edges, upturned extremities and means thereon to engage the sole or heel.

2. An anti-gripping device for boots, shoes and the like, consisting of a single length of

resilient material having an intermediate region sinuously bent and formed lengthwise with confronting gripping edges, and upturned extremities for embracing the sole or heel elements. 10

In testimony whereof I have signed my name to this specification.

GEORGE HEITLER.
